(57) **CLAIM**

We claim the ornamental design for a flashing component for a self-flashed skylight, as shown and described.

DESCRIPTION

FIG. 1 is a perspective view of the flashing component for a self-flashed skylight of the present disclosure;

FIG. 2 is a bottom plan view thereof;

FIG. 3 is a cross-sectional view taken along line 3—3 of FIG. 1;

FIG. 4 is a perspective view of a frame element of the flashing component for a self-flashed skylight taken from the right side in FIG. 3;

FIG. 5 is an enlarged elevation view of the right side in FIG. 3;

FIG. 6 is a perspective view of a frame element of the flashing component for a self-flashed skylight taken from the left side in FIG. 3; and,

FIG. 7 is an enlarged elevation view of the left side in FIG. 3.

The ornamental design that is claimed is shown in solid lines in the drawings. The portions of the design shown in broken lines do not constitute part of the claimed design and are, therefore, disclaimed.
